ARTIFICIAL LIMB

Harry M. Witmyer and William R. Simpson, Jr.,
Manheim, Pa.

Application May 23, 1945, Serial No. 595,338

12 Claims. (Cl. 287—88)

1

The present invention relates to artificial limbs and particularly to means for connecting together two limb portions in such manner that these portions may be freely moved relatively to each other, as desired, through various angles up to a predetermined maximum angle.

The improved connecting means may be employed to connect together an artificial leg and an artificial foot, or utilized to connect together two arm members, or wherever it is desired to pivotally attach together the artificial counterparts of members of the human body. When the improved connection is employed as means for pivotally attaching an artificial foot to the lower portion of an artificial leg highly advantageous results are realized, the connection having been so designed that it will, when used in the customary manner, minimize fatigue and tensional strains of the leg muscles of the wearer. The weight of the body which is intermittently placed on the artificial leg in the normal operation of walking will be transmitted by the novel connecting means to the foot and thence to the ground in a manner which is a precise simulation of the manner in which the weight of the body is transmitted through the normal ankle and foot to the surface beneath. In modified forms it may readily be utilized in the connection of other artificial limb members, as will be apparent to one skilled in the art, and wherever used provides a means for connecting two parts which is extremely simple in its construction, and durable in use so as to give long, continued service with only slight wear of the relatively movable parts. It is of moderate first cost and, by reason of the simplicity and ruggedness of its design, will endure for very long periods of time without need for other than routine and infrequent adjustment. It may be readily attached to the limb parts or members which it connects and when so attached will remain securely fastened to these parts, the attachment devices being of unusually simple but effective design.

In the accompanying drawings two slightly different embodiments of the invention are illustrated by way of example, the novel connecting means being in each case shown to connect an artificial foot to the lower end of an artificial leg. It will be appreciated that it may be otherwise employed, as previously stated, and that the design and arrangement of the component elements of the joint may be modified in minor respects when adapting the same for the connection of other artificial limb members.

In the drawings:

2

Figure 1 is a view showing in axial section the lower end of an artificial leg member and, partially in elevation and partially in section, an adjacent artificial foot member, the novel device for pivotally connecting these members being shown in axial section and the leg member and foot member being illustrated in the relative positions which these two parts normally occupy when the wearer is standing upright;

Figure 2 is a similar view but showing the artificial limb members in different relative positions, for instance in the relative positions which they occupy when the wearer of the artificial limb is taking a step;

Figure 3 is a section on line 3—3 of Figure 1;
Figure 4 is a section on line 4—4 of Figure 1;
Figure 5 is a section on line 5—5 of Figure 1; and

Figures 6, 7 and 8 are sections through a somewhat modified form of artificial limb joint construction, these figures corresponding, respectively, to Figures 1, 2 and 3.

The lower end of the artificial leg illustrated in Figures 1 through 5 is indicated by the numeral 10 and the artificial foot is indicated by the numeral 11. The device for pivotally connecting these parts is of the ball and socket type, but embodies novel features of construction not found in devices of this general nature which have heretofore been designed or suggested. The socket member is indicated at 12 and preferably this member has a generally cylindrical outer surface with the upper end of slightly smaller diameter than the lower end, thus providing an annular shoulder 13 which faces upwardly. The socket member is adapted to seat snugly within a correspondingly shaped aperture or recess formed in the lower end of the limb member 10 and to be secured in the position in which it is shown by means of bolts 14 and 15 which pass through aligned apertures formed in the limb and socket members, as shown in Figure 5 of the drawings, the bolts 14 and 15 being either provided with nuts such as 16 and 17, located in countersunk recesses formed in the member 10, or being headed-over, so as to permanently secure the socket member 12 in position. At its upper end the socket member is provided with a cylindrical axial recess 18 and its lower concave substantially spherical surface 19 is also described about a point on the axis of the member 12. A short cylindrical axial passage 20 connects the spherical recess in the lower end of the socket member 12 with the axial recess 18 in the upper end of this member and within this passage 20 is dis-

posed a closely fitting bolt 21 the head 22 of which is within the recess 18 and the shank of which projects downwardly beyond the lower end of the socket member 12 and has, at its terminal end, a reduced threaded portion 23 upon which a nut 24 is threaded. By reason of the close fit of the shank 21 of the bolt in the cylindrical aperture 20 of the socket member 12 the bolt is constrained to move with the socket member at all times and may be considered to be a downwardly extending axially disposed portion of the socket.

The ball member of the connecting device is indicated generally at 30 and is seen to comprise an upper substantially spherical portion 31, the surface of which snugly engages at all times the spherical surface 19 of the socket member 12, and a downward extension 32 in the nature of a hollow tube the axis of which is coaxial with the axis of the upper spherical portion 31. The lower end surface of the hollow tubular portion 32 of the ball is spherical, being centered at C, which is the center of the spherical surface of the upper portion 31 of the ball. Bearing against the spherical lower end surface of the part 32 of the ball is the upwardly facing spherical surface of the nut 24. A lock nut 24a prevents nut 24 from backing off and insures that the ball member is firmly engaged by the socket member 12 on one side and the nut 24 on the other.

The axial aperture formed in the ball 30 through which the bolt 21 extends is circular in all transverse sections and is narrowest midway between its ends, as clearly shown in Figures 1 and 2. Thus, from its midpoint it flares both upwardly and downwardly, the purpose being to provide the bolt 21 with space through which the bolt may oscillate or rock about its center of oscillation or rocking movement, i. e., the center of the ball member, when the device is in operation. When the socket 12 moves relatively to the ball 30 the bolt will move angularly about the point C, which is the center of the spherical surfaces of the ball and it is clear that the extent of rocking movement or oscillation of the bolt about the point C will be limited by the contact of the bolt with the walls of the aperture in the ball within which it is located. In Figure 2 of the drawings the bolt is shown to have been tilted or rocked to the limit of its tilting or rocking movement in one direction. The angle through which the bolt may rock from a central position may, of course, be modified by increasing or decreasing the degree of taper or flare of the upper and lower sections of the bolt-receiving recess in the ball.

The ball is securely attached to the artificial foot 11, the lower end of the tubular portion 32 of the ball being exteriorly threaded so as to receive a securing nut 35, the upper surface of this nut being parallel to the undersurface of the spherical portion 31 of the ball so that these two surfaces are adapted to clampingly engage an intermediate annular portion 11a of the artificial foot 11. Suitable locking means, such as screw 35a, may be provided to prevent accidental loosening of nut 35, this screw being received in a threaded aperture in the nut and its pointed end being pressed into the annular portion 11a of the foot. In assembling the device with the members 10 and 11 the ball will be secured firmly to the foot member 11 by means of the nut 35 and the socket, with the bolt 21 disposed within the opening 20, to the leg member 10 by means of the securing bolts 14 and 15. The ball and socket members may then be placed in cooperative rela-

tionship and the bolt 21 positioned as shown, the ball-engaging nut 24 then being applied in such manner that part 34 closely engages the spherical lower end surface of the tubular part 32 of the ball. The parts are then in operative relationship and the lock nut may then be applied to insure that this relationship is maintained. The mouth of the aperture in the foot is then sealed to prevent the entry of dirt, a wooden or composition disc 46 being inserted and secured in position by means of a screw 47.

In order to prevent the foot member 11 from rotating about the longitudinal axis of the leg member 10, i. e., from rotating about the axis of the bolt 21, it is provided with inserts or plugs 40 the upper ends of which project respectively into recesses 41 formed in the lower surfaces of the leg portion 10. The lower end surfaces of the leg portion 10 are spaced from the substantially parallel mutually facing surfaces of the foot portion 11 and there is placed intermediate these mutually facing surfaces a resilient gasket-like member 43 which is preferably of rubber. The resilient member 43 functions to maintain the ball and socket in coaxial relationship in the absence of any force tending to move these parts angularly with relation to each other, as when the user is walking, while at the same time not interfering with, although cushioning, the angular relative movement of the connected leg members. Preferably the plugs 40 are formed as integral portions of the annular rubber member 43. Additional plugs 40a are located upon opposite sides, respectively, of the joint device, being located in aligned recesses, respectively, and preferably integral with member 43.

It will be seen from Figure 2 that if the foot moves angularly with respect to the leg member that portion of the rubber cushion which lies to one side of the connecting device will be compressed and that portion of the cushion which lies to the other side of the connecting device will be allowed to expand. The arrangement is such, therefore, that the wearer is not subjected to mechanical shock as the foot reaches the limit of its movement with respect to the leg and the action is very much the same as that of the normal ankle. The socket may with advantage be fabricated of asbestos fiber treated with phenolic resins, or of textile fibers similarly treated. It may be formed of such materials by securing together sheets or laminations thereof, the assembled sheets then being machined if necessary. The socket may have a lubricant such as graphite incorporated therein so as to maintain the interengaging surfaces of the ball and socket satisfactorily lubricated for the life of the connecting device. Naturally, however, the socket may be fabricated of other suitable materials, such as resin-treated pulps, or steel, bronze, brass, cast iron, aluminum or aluminum alloys. The connection may be made of various sizes to be incorporated in limbs for the use of adults or children.

In Figures 6, 7 and 8 there is shown a generally similar form of artificial limb member connecting device. Here the socket member 60 is connected to the limb member 61 by bolts 62 identical with those shown in Figures 1 and 5, but located relatively close to the ball-engaging surface of the socket. The sealing member 63 is of somewhat different design and the rubber plugs 64 and 65 somewhat larger. All of these plugs are shown to be formed integrally with the rubber gasket 66. A sleeve 68 encircles the gap

between the limb members to prevent penetration of dust and dirt to the connecting ball joint. This sleeve may be attached to the leg member or to the foot member as desired. A similar sleeve 69 is employed in association with the limb members of the form of the invention illustrated in Figures 1, 2 and 3.

If desired the rubber gasket, with its associated plugs or enlargements, may be of such thickness that it is under some compression at all times, both when the limb members are in normal relative position or in the relative positions in which they are shown in Figures 4 and 7. In such constructions spongy rubber may be utilized to insure that the relative angular movements of the limb members may not be restricted. The limb members may be constructed of any suitable material, the foot member being preferably fabricated of wood.

Having thus described the invention, what is claimed as new and desired to be secured by Letters Patent is:

1. In an artificial limb, the combination with two parts to be connected together for limited angular movement of a ball mounted on one of said members and a ball-engaging device mounted upon and movable with the other member, said ball-engaging device including elements adapted to engage diametrically opposed spherical surfaces of the ball, and means connecting said elements and maintaining them in close sliding engagement with such surfaces of the ball.

2. In an artificial limb, the combination with two parts to be connected together for limited angular movement of a ball mounted on one of said members and a ball-engaging device mounted upon and movable with the other member, said ball-engaging device including elements adapted to engage diametrically opposed spherical surfaces of the ball, and means connecting said elements and maintaining them in close sliding engagement with such surfaces of the ball, said means and ball having mutually engageable portions comprising stops for limiting the relative angular movements of the ball and ball-engaging device.

3. In an artificial limb, the combination with two parts to be connected together for limited angular movement of a ball mounted on one of said members and a ball-engaging device mounted upon and movable with the other member, said ball having an aperture extending therethrough and said ball-engaging device including elements adapted to engage diametrically opposed spherical surfaces of the ball and means extending through the aperture in the ball for connecting said elements and maintaining them in close sliding engagement with such surfaces of the ball.

4. In an artificial limb, the combination with two parts to be connected together for limited angular movement of a ball mounted on one of said members and a ball-engaging device mounted upon and movable with the other member, said ball having an aperture extending therethrough and said ball-engaging device including elements adapted to engage diametrically opposed spherical surfaces of the ball and a bolt extending through the aperture in the ball for connecting said elements and maintaining them in close sliding engagement with such surfaces of the ball, contact between the bolt and ball limiting relative angular movements of said members.

5. The combination set forth in claim 4 in

which the aperture in the ball varies in cross section from end to end, flaring outwardly toward both ends from its midpoint, angular movement of the bolt relatively to the ball being limited by contact of the bolt and wall of the aperture.

6. The combination set forth in claim 4 in which the bolt is provided with a nut for relatively adjusting the ball-engaging elements.

10 7. The combination set forth in claim 1 in which one of said elements is formed as a substantially cylindrical block having at one end a spherical surface for engaging the ball and at the other end transversely extending apertures 15 for the reception of securing bolts, and securing bolts extending through said apertures and through the part with which said block is associated.

8. For use in connecting parts of artificial limbs, a ball member having a substantially hemispherical portion and an integral hollow radially extending tubular portion with a spherical end surface, the hemispherical portion having an aperture therein which is aligned with the aperture of the tubular portion, a nut encircling and having threaded engagement with the tubular portion of the ball whereby the ball may be clamped to an annular limb part intermediate the nut and hemispherical portion of the ball, and means to be mounted upon a second limb part, said means being provided with elements for engaging said aforementioned spherical surfaces of the ball.

9. For use in connecting artificial limb parts, 35 a ball comprising coaxial hemispherical and radially extending portions, the outer end surface of the radially extending portion being curved spherically about the axis of curvature of the hemispherical portion, a nut encircling and threaded upon said radially extending portion whereby a limb part may be clamped between the hemispherical portion of the ball and said nut, and means to be mounted upon a second limb part, said means being provided with elements for engaging said aforementioned spherical surfaces of the ball.

10. An artificial limb comprising two parts and a device for connecting the same for universal movement about a central point, resilient means 50 interposed between said parts and normally maintaining them in a predetermined angular relationship, and second means offset laterally from said device for limiting relative rotation of said parts about an axis extending longitudinally of one of them.

11. An artificial limb comprising two parts and a device for connecting the same for universal movement about a central point, resilient means interposed between said parts and normally 60 maintaining them in a predetermined angular relationship, and second means offset laterally from said device for limiting relative rotation of said parts about an axis extending longitudinally of one of them, said second means including a resilient member intermediate said parts and adapted to assist in maintaining them in predetermined angular relationship as well as to limit their relative rotation about an axis extending longitudinally of one of them.

70 12. An artificial limb comprising two parts and a device for connecting said parts for universal movement about a central point, the adjacent ends of said parts having registering recesses, and a resilient member extending into said recesses, said member opposing relative rotation

of said parts about an axis extending longitudinally of one of them.
